US0D1091303S

(12) **United States Design Patent** (10) Patent No.: **US D1,091,303 S**
 Mayer (45) Date of Patent: ** Sep. 2, 2025

(54) **TAMPER EVIDENT FEATURE**(71) Applicant: **Inno-Pak, LLC**, Delaware, OH (US)(72) Inventor: **Steven A. Mayer**, Indianapolis, IN (US)(73) Assignee: **Inno-Pak, LLC**, Delaware, OH (US)(***) Term: **15 Years**(21) Appl. No.: **29/978,290**(22) Filed: **Dec. 12, 2024****Related U.S. Application Data**

(62) Division of application No. 29/828,418, filed on Feb. 25, 2022, now Pat. No. Des. 1,060,029.

(51) LOC (15) Cl. **09-03**

(52) U.S. Cl.

USPC ..... **D9/416; D9/433**(58) **Field of Classification Search**

USPC D9/414, 418, 420, 423, 424, 425, 432, D9/737, 743, 744, 745, 761; D7/541, D7/542, 553.1, 553.2, 554.3, 602, 629, D7/701, 703, 708; D3/201, 203.3, 273,

(57) CLAIM

The ornamental design for a tamper evident feature, as shown and described.

DESCRIPTION

FIG. 1 is a front perspective view of a tamper evident feature with the tamper evident feature shown in a first open untampered configuration;

FIG. 2 is a front perspective view of the tamper evident feature of FIG. 1 with the tamper evident feature shown in a second open untampered configuration;

FIG. 3 is a front perspective view of the tamper evident feature of FIGS. 1 and 2 with the tamper evident feature shown in a closed untampered configuration;

FIG. 4 is a rear perspective view of the tamper evident feature of FIG. 2;

FIG. 5 is a front elevation view of the tamper evident feature of FIG. 3 shown in a closed configuration;

FIG. 6 is a rear elevation view of the carton of FIG. 3 with tamper evident feature;

FIG. 7 is a left side elevation view of the tamper evident feature of FIG. 3;

FIG. 8 is a right side elevation view of the tamper evident feature of FIG. 3;

FIG. 9 is a top plan view of the tamper evident feature of FIG. 3;

FIG. 10 is a bottom plan view of the tamper evident feature of FIG. 3;

FIG. 11 is a front perspective view of the tamper evident feature of FIG. 3 shown with a tamper evident strip of the tamper evident feature partially removed;

FIG. 12 is a first plan view of the tamper evident feature of the carton of FIG. 1 shown in a flat unfolded configuration; and,

FIG. 13 is a second plan view of the tamper evident feature of the carton of FIG. 1 shown in a flat unfolded configuration.

In the drawings the dash-dash broken lines are for the purpose of illustrating environment only and form no part of the claimed design.
